US0D1034058S

(12) **United States Design Patent** (10) Patent No.: **US D1,034,058 S**
 Vandesteene (45) Date of Patent: ** Jul. 9, 2024

(54) **SURFACE ORNAMENTATION FOR A FOOD TRAY**

(71) Applicant: **Gastroca Trading, S.L.**, Irún (ES)

(72) Inventor: **Jean-François Vandesteene**, Irún (ES)

(73) Assignee: **GASTROCA TRADING S.L.**, Irún (ES)

(**) Term: **15 Years**

(21) Appl. No.: **35/513,875**

(22) Filed: **Sep. 20, 2021**

(80) **Hague Agreement Data**

Int. Filing Date: **Sep. 20, 2021**

Int. Reg. No.: **DM/217093**

Int. Reg. Date: **Sep. 20, 2021**

Int. Reg. Pub. Date: **Mar. 25, 2022**

(51) **LOC (14) Cl.** 07-99

(52) **U.S. Cl.**

USPC **D7/396.4; D7/567**

(58) **Field of Classification Search**
